UNITED STATES PATENT OFFICE.

JAMES B. BANKSON, OF CANTON, SOUTH DAKOTA.

WIRE-FENCE STRETCHER.

988,065.

Specification of Letters Patent. Patented Mar. 28, 1911.

Application filed May 25, 1910. Serial No. 563,426.

To all whom it may concern:

Be it known that I, JAMES B. BANKSON, a citizen of the United States, residing at Canton, in the county of Lincoln and State 5 of South Dakota, have invented certain new and useful Improvements in Wire-Fence Stretchers, of which the following is a specification.

The invention relates to devices for 10 stretching woven-wire fence, and it consists of one or more screw-threaded rotatable feed-rods carrying travelers, said travelers being arranged to travel in opposite directions, and suitable gearing for actuating the 15 rods.

The invention further consists of the general construction and arrangement of the several parts, as will be hereinafter fully described herein, and briefly stated in the 20 claims.

One of the chief objects of the invention is to provide a device of the character mentioned which shall be of simple and inexpensive construction, and at the same time 25 durable and efficient in operation.

Other objects of the invention will become apparent upon a complete disclosure thereof.

In the drawings: Figure 1 is a top plan view; Fig. 2 is an edge view of one of the 30 travelers, and Fig. 3 is an edge view of the operating crank.

Referring to the several views, the numeral 1 indicates a suitable frame, preferably rectangular in shape, provided with a 35 narrowed extension 2. The frame is provided with a cross-bar 3, and a longitudinal bar 4 divides the frame into two spaces 5 and 6. Journaled in the cross-bar is a screw-threaded feed-rod 7, which extends into a 40 space 5 and has its head provided with a bevel gear-wheel 8 meshing with similar gear-wheel 9, mounted on a shaft 10, journaled in the sides of the frame. Also journaled in the cross-bar 4 is a screw-threaded 45 feed-rod 11, which extends into the space 6 and has its head provided with a bevel gear-wheel 12 meshing with a similar gear-wheel 13 mounted on the shaft 10. Mounted on the shaft 10, between the gear-wheels 9 and 50 13, is a cog-wheel 14, and mounted on a shaft 15, journaled in the side walls of the extension, is a small, driving cog-wheel 16 which meshes with the larger cog-wheel 14. The shaft 15 is provided with a squared

head, as shown, as is also the shaft 10, to receive the operating-crank 17, by means of which either shaft may be driven to cause, through the medium of the bevel gears, the rotation of the screw-threaded feed-rods.

The feed-rod 7 carries a traveler 18 and 55 the feed-rod 11 carries a traveler 19, each traveler including a screw-threaded nut 20 and a link 21 which has one end terminating in a flattened extension 22, to which is loosely-attached, a hook 23. In operation, 60 the extension end of the stretcher will be attached to a fence-post, and the end of either traveler to any suitable attaching means with which the edge of the woven-wire fence 65 may be provided, by means of the hook 23, 70 it being understood that whichever traveler is so attached must be positioned at the outer end of its feed-rod, so that when either shaft is rotated the traveler will move up the rod, stretching or tightening the fence in its 75 movement. If the other traveler, for instance 18, which has been out of commission during the operation, is positioned at the inner end of its feed-rod it will be moved toward the outer end of said rod as the latter 80 revolves, so that when the traveler 19, that is connected with the fence, has reached the limit of its inward movement, the other traveler 18 will have reached the limit of its 85 outward travel, and in position to be connected with the fence upon the detachment of the traveler 19. When the traveler 18 has been connected to the fence and the traveler 19 disconnected, the driving-shaft 90 is operated in a direction reverse to its former revolution, whereby the traveler 18 will be caused to move inward to stretch or tighten the fence, and the traveler 19 moved outward, thus it will be seen that the 95 travelers are operated alternately in stretching or tightening the fence, thereby saving time and labor in the operation.

By operating the shaft 15 to cause cog-wheel 16 to drive cog-wheel 14, increased power in revolving the feed-rods is obtained, 100 and increased leverage may be obtained by lengthening the crank-arm 17, which is composed of two members 24 and 25, the latter having bent-portions 26 and 27, respectively, provided with slots through which the member 24 is adapted to slide, a set-screw 28 being provided to secure the members together at the desired length. The outer end of the 105

member 25 is provided with a rectangular opening 29 to receive the squared end of the shafts.

Having thus described my invention, what I claim is:

- 5 1. A wire-fence tightener, having in combination a suitable frame, a pair of travelers mounted on screw-threaded rods journaled in said frame, a wire engaging member attached to each follower, and means for revolving said rods, said travelers being so positioned on said rods that they will be caused to move in opposite directions, whereby one traveler will be doing the work required, while the other will be moving to working position.
- 10 2. A wire-fence tightener, comprising a frame divided longitudinally into two spaces, a traveler movable in each space, a wire engaging member attached to each follower, and means for moving the travelers in
- 15
- 20

opposite directions, whereby one traveler will be doing the work required while the other will be moving to working position.

3. A wire-fence tightener, comprising a frame divided longitudinally into two spaces and provided with a cross-bar, a screw-threaded rod operative in each space and journaled in said cross-bar, a traveler movable on each rod, a wire engaging member attached to each follower, and means for revolving said rods to move the travelers in opposite directions, whereby one traveler will be doing work while the other is assuming a position to commence doing work. 35

In testimony whereof I affix my signature in presence of two witnesses.

JAMES B. BANKSON.
